[57] CLAIM

The ornamental design for a wall mounted display
holder for visored caps, substantially as shown and
described.

DESCRIPTION

FIG. 1 is a front view of a wall mounted display holder
for visored caps showing my new design;
FIG. 2 is a rear view thereof;
FIG. 3 is a top view thereof;
FIG. 4 is a side view taken from the right of FIG. 1;
FIG. 5 is a bottom view thereof.
